162,930

VAPORIZER

William A. Brukoff, Chicago, Ill.

Application July 13, 1949, Serial No. 3,901

Term of patent 7 years

(Cl. D83—1)

To all whom it may concern:

Be it known that I, William A. Brukoff, a citizen of the United States, residing at 501 Diversey Parkway, Chicago, Illinois, have invented a new, original, and ornamental Design for a Vaporizer, of which the following is a specification, reference being had to the accompanying drawing, forming a part thereof.

In the drawing:

Figures 4 and 5 are sectional views taken, respectively, on the lines 4—4 and 5—5 of Figure 1; and

I claim:

The ornamental design for a vaporizer, substantially as shown.

WILLIAM A. BRUKOFF.
